INVENTOR:

LESLIE R. VON PONGRACZ.

BY

Louis V. Lucia

ATTORNEY.

WALL MOUNTED BOOTH

BACKGROUND OF THE INVENTION

Known booths generally include a table and seats which are separately supported adjacent to said table.

The general object of this invention is to provide an improved structure for a booth in which the table and the chairs are all mounted upon a single unitary frame having a table supporting bracket member which may be secured to a wall and a horizontal U-shaped seat supporting member secured to said bracket member and having seat supporting side portions extending perpendicularly from the wall and supporting a plurality of seats at opposite sides of said table: said bracket supporting the entire booth as a complete unit.

BRIEF DESCRIPTION OF THE DRAWING

FIG. 1 is an isometric view showing the structure of the frame for my improved booth.

FIG. 2 is an isometric view of the complete booth.

DESCRIPTION OF THE INVENTION

As shown in the drawings, the said booth includes a frame having an inverted L-shaped supporting bracket member 5 with a wall engaging portion 6 and a table supporting portion

5 portions for mounting seats thereon.

7. A horizontal U-shaped seat supporting member is secured to said bracket member and has side arm portions 8-8 extending perpendicularly from the bracket portion 6 and seat mounting plates 9 secured to the upper edges of said arm portions for mounting seats thereon.

As shown in FIG. 2 a table 10 is secured to the portion 7 of the bracket 5 by means of screws inserted through the holes 11 and the seats 12 are secured to the mounting plates 9 by screws inserted through the holes 13 thereof.

10. When so assembled, the entire booth will be contained as a complete unit which may be easily mounted upon a wall in any desired location.

I claim:

15. 1. A wall mounted booth including a supporting frame having an inverted L-shaped bracket member with a flat wall engaging portion and a horizontal table supporting portion extending therefrom, a horizontal U-shaped member secured to said wall engaging portion and having parallel seat supporting arms extending perpendicularly therefrom, a table mounted upon said table supporting portion, and seats mounted entirely upon said seat supporting arms.

20. 2. The subject matter set forth in claim 1 including mounting plates upon said supporting arms for said seats.
